UNITED STATES PATENT OFFICE.

JAMES N. REYNOLDS, OF CLEVELAND, OHIO.

DEVICE FOR BENDING METAL RODS OR TUBES.

Application filed March 5, 1921. Serial No. 449,815.

To all whom it may concern:

Be it known that I, JAMES N. REYNOLDS, a citizen of the United States, residing at Cleveland, in the county of Cuyahoga and State of Ohio, have invented a certain new and useful Improvement in Devices for Bending Metal Rods or Tubes, of which the following is a full, clear, and exact description, reference being had to the accompanying drawings.

My invention relates to a device for bending metal rods or tubes, one object being to provide a simple and efficient device of this character which shall be made of few parts and be cheap in manufacture. Another object is to provide a device which may be readily adjusted to bend rods of various sizes and on various radii. Other objects of the invention will be apparent in the course 20 of the following description and the features of novelty will be pointed out in the claims.

In the drawings in which a preferred embodiment of my invention is illustrated, Fig. 1 is a plan view of the device with the upper casing plate 50 removed; Fig. 2 is a fragmentary view of a portion of Fig. 1, showing a guide plate having a curved end of slightly larger diameter than that shown in Fig. 1; Fig. 3 is a fragmentary section on the line 3—3 of Fig. 1; Fig. 4 is a plan view with a portion of the plate 12 broken away to show the underlying mechanism in full lines; Fig. 5 is an end view of the device as illustrated in Fig. 1 and showing it attached 35 to a standard; Fig. 6 is a plan view of the device on a smaller scale and showing the completely assembled device of the casing plate in position.

The device in general comprises a guideway for guiding a rod and a member movable transversely of the guideway, one guide member having a curved face adapted to form the rod as the transversely moving member forces it against the curved end of the guide. Referring more specifically to the drawings and to the different parts by reference numerals, the device as illustrated comprises a lower plate 10, which may be provided with end flanges 11 by means of which a plate 12 may be held on the first named plate and spaced therefrom. The device is adapted to be suitably attached to a standard, as shown in Fig. 5, by means of the bolts 15 passing through suitable openings in the plate 10.

The upper plate 12 has secured thereto a suitable guide means such as the slides or guides 20, 21. These members have opposed faces forming a guideway adapted to direct a rod or tube of metal and the member 20 is provided with a suitable curved end 22. Movable transversely of the guideway so formed and situated beyond its end is a roll 30, which is adapted when operated to force the rod in the guideway against the curved end 22 of the guide 20 as shown in Fig. 2. In the bending of metal rods it is desirable that the rod shall be bent on a radius not less than the radius of the rod and the curved face 22 should therefore be of a radius at least as great as that of the rod being operated upon. In order to adapt the machine for bending rods of different sizes, I show the guide member 20 as readily detachable from the frame, so that it may be replaced by a guide having a suitably formed curved end.

While it is desirable that the radius of curvature shall be at least as great as that of the rod, the rod may of course be bent on a larger radius, but in order to form a smooth bend the roll should pass close to the bending guide and preferably to a distance equal to the diameter of the rod. In order that the same guide member may be adapted 80 for use with different sizes of rods it is therefore necessary that an adjustment be provided for moving the guide relative to the path of the transversely movable member and for this purpose I have shown the member 20 as slidably mounted on the plate 12 and guided by means of undercut flanges 16 which extend parallel to the guide face of the member 20, and serve to hold it 85 against lateral shifting.

In order to provide a positive means for adjusting the member 20 towards and from the path of the roll 30, and for maintaining it in adjusted position I have shown the set screws 17 abutting the edge of the guide 20 and threaded in the flange 18 extending transversely of the flanges 16 and suitably secured to the plate 12. I prefer also to provide still further holding means for the guide 20, which is shown herein as consisting of the bolts or screws 19 extending through slots in the guide 20 and threaded in the plate 12.

By means of this adjustment, the end of the guide may be brought into proper rela-

tion with the pathway of the transversely moving roll 30. In Fig. 2 I have illustrated a guide member 20', which has an end of slightly larger radius of curvature than that of member 20, shown in Fig. 1. This member corresponds in all other respects with member 20.

The guideway for the rod should snugly fit the rod in order to insure correct bending thereof, and therefore means should be provided for varying the width of this guideway. I accomplish this result in the device illustrated by mounting the guide 21 on the guide 20 so that it may be moved transversely thereof, and I show suitable means for bringing about this adjustment and for holding the plate in adjusted position. The means for accomplishing this result consists of positioning screws 25 which are threaded through a longitudinal flange carried by the guide 20 and which screws abut a side of the guide 21. I may also provide the screws 24 projecting through slots in the guide member 21 and threaded in the guide 20 which screws constitute an additional means tending to maintain the guide 21 in position on guide 20. I also show this guide 21 as abutting the end flange on the guide 20 which assists in preventing the disalignment of the guide member.

It will be seen, therefore, that the screws 17 and 25, respectively, serve as means to take up the thrust exerted upon the guides 20 and 21, respectively, when the metal rod is being bent by the action of roll 30, while the screws 19 and the flanges 16 in the case of guide 20, and the screws 24 and the end flange on member 20, in the case of guide 21, also assist in holding the guides in position.

40 In order to provide protection for the set screws for positioning the guide members, I prefer to provide a protecting plate or casting which may be suitably secured to the plate 12 and which has cut away portions to allow access to the guide members and room for manipulation of the handle 40, as is clearly shown in Fig. 6.

In order to operate the bending roll 30 with the requisite force I show this roll journaled at one end in the lever 31 and at its other end in the angle member 32, which may be suitably secured on the lever. The lever 31 is shown as lying between the plates 10 and 12 and to provide a pivot for this lever, I have shown a pin 33 having reduced ends extending into the plates 10 and 12 and passing through an opening in the lever 31, suitable sleeve bushings 34 being provided to hold the lever in position longitudinally of the pivot member. The roll 30 extends upwardly through an arcuate slot 14 in the plate 12, having the pivot point 33 as its center so as to allow the swinging of the roll on this pin as center.

65 In order to actuate the lever and roll by

a power multiplying mechanism, I have shown the lever as connected by means of the link 35 with a lever 40 pivoted intermediate of the plates 10 and 12 by means of pin 41 in the same manner as the lever 31 is mounted. The link 35 is connected to the lever 31 at the point 36 and to the lever 40 at the point 42, the distance from 33 to 36 being greater than the distance from 41 to 42, whereby the lever 31 will have a smaller angular motion than the lever 40. The outer end of the lever 40 is suitably formed to be grasped by the hand of the operator.

It will be seen that I have devised a very simple mechanism which is adapted to quickly and smoothly bend a rod, tube or the like. The device consists of very few parts and adjustable mounting of the guide members allows the adjusting whereby the device may operate upon rods of varying sizes, while the ease with which these guides may be removed and replaced allows the device to be readily adjusted to vary the radius of curvature formed at the bend of the rods.

My device, by providing positive means for taking up the thrust on the guides which occurs during the bending operation, insures the maintenance of these members in correct position so as to cause a smooth bend of the article operated upon.

While I have described a specific embodiment of the invention it will be understood that many changes might be made therein, and that various other forms of device might be constructed embodying the principles of my invention, and the foregoing description is to be taken as illustrating a particular embodiment of the invention rather than restricting the character and scope of the invention.

Having thus described my invention, I claim:

1. In a rod bending machine, a frame having an upper plate, guide members mounted on said plate and forming a guideway for rods to be bent, there being a slot in said plate adjacent the end of said guideway, a pivoted member mounted to move beneath said plate and having a bending roll extending through said slot, means for moving said bending roll in the slot to bend a rod held in said guideway, said means including a hand lever pivoted on said frame and means connecting the hand lever to the pivoted member whereby the latter may be actuated.

2. In a rod bending machine, a base member and an upper plate spaced therefrom, a member pivoted to the base and the plate, an operating lever pivoted to the base and the plate adjacent said member, a link connecting said member and the lever, an angle bracket secured to said member and having a bearing for a bending roll therein, a bending roll fitted in said bearing and having its

lower portion abutting said member, there being a slot in said plate through which said bending roll projects.

3. In a rod bending machine, a base member and an upper plate spaced therefrom, a substantially triangular shaped member pivoted to the base and the plate, an operating lever pivoted to the base and plate adjacent said triangular shaped member, a link connecting said triangular shaped member and the lever, an angle bracket secured to the triangular shaped member and having a bearing for a bending roll therein, a bend-

ing roll fitted in said bearing and having its lower portion abutting said substantially triangular shaped member, there being a slot in said plate through which said bending roll projects and a holding member for material to be bent having an anvil located adjacent said slot, said anvil being movable toward and from said slot whereby bars of different sizes may be bent.

In testimony whereof, I hereunto affix my signature.

JAMES N. REYNOLDS.
